UNITED STATES PATENT OFFICE.

MARTIN W. PERKINS, OF BATTLE CREEK, MICHIGAN.

BLACKBOARD-ERASER.

No. 873,827.

Specification of Letters Patent.

Patented Dec. 10, 1907.

Application filed February 24, 1903. Serial No. 144,692.

To all whom it may concern:

Be it known that I, MARTIN W. PERKINS, a citizen of the United States, residing at the city of Battle Creek, in the county of Calhoun 5 and State of Michigan, have invented certain new and useful Improvements in a Blackboard-Eraser, of which the following is a specification.

This invention relates to erasers, and is 10 particularly designed to provide an improved device of this character for use in cleaning blackboards.

It is furthermore designed to arrange the device for convenience in manipulation, and 15 to have the entire eraser flexible and free from rigid parts, so as to effectually obviate damage to the blackboard when cleaning the same.

Another object of the invention is to have 20 the device in a form that is especially adapted for taking up chalk dust, and also in such form as to present a comparatively large cleaning surface and at the same time to effectually fit the hand and thereby facilitate 25 the manipulation thereof.

With these and other objects in view, the present invention consists in the combination and arrangement of parts as will be herein-after more fully described, shown in the ac- 30 companying drawing and particularly pointed out in the appended claims.

In the drawing: Figure 1 is a perspective view of a black board eraser embodying the features of the present invention. Fig. 2 is a 35 bottom plan view thereof; and, Fig. 3 is a cross-sectional view of the eraser.

Like characters of reference designate cor- 40 responding parts in each and every figure of the drawing.

As hereinbefore indicated, it is an impor- 45 tant object of the present invention to provide a comparatively large cleaning surface and at the same time to have the device in a form which is convenient for handling, and to 50 carry out this object, a circular form has been selected, and the body of the eraser is composed of a single continuous length of felt or other suitable material 1, which is tightly coiled upon itself to form a flat disk-shaped body, the outer end of the strip of felt being 55 tapered or reduced in thickness, so as to pre- serve as far as possible the circular or disk shape of the body, and this reduced end por- tion is secured to the adjacent peripheral edge portion of the body by means of 60 stitches 2.

The top and bottom of the body are flat, and the top is provided with a back, desig- 60 nated by the reference character 3, and formed of some strong, durable and flexible material, preferably leather, which is designed to hold the coils of the felt strip in place by being held thereto by glue or other adhesive material. This flexible back of the eraser is a very important feature of the invention, as 65 it holds the coils of the felt strip together in close proximity and at the same time permits of some flexibility so as to permit of the eraser accommodating itself to unevennesses in a blackboard, to permit of the chalk dust 70 being taken up in the joints between the coils, and to obviate the usually rigid part of an eraser, which is liable to injure the board when it is accidentally brought violently into contact therewith. In the absence of a 75 wooden or other rigid back, the eraser may be manipulated with freedom and without any particular care, as there is no danger of damaging the board with any part of the eraser.

To facilitate the handling of the eraser, there is provided a handle 4, in the form of a loop, formed by a flexible strap, preferably of leather, with its ends passed inwardly through slits or incisions 5, in the back and 80 then inserted between the back and the coil of felt, where it is glued to the coil and the back. The intermediate portion of the strap is sufficiently loose as to permit of the fingers of the hand being thrust through the loop- 85 shaped handle and then grasped upon the per- 90ipheral edge of the body, whereby the eraser may be conveniently manipulated in cleaning a blackboard.

From the foregoing description, it is ap- 95 parent that the device of the present invention is very simple, inexpensive and durable, and in view of its flexibility is particularly well adapted to effectually take up chalk dust, and in this particular it is a sanitary de- 100 vice. Furthermore, its flexibility prevents injury to the blackboard and renders its ma- nipulation easier and more comfortable.

Although the eraser has been shown and described as circular in shape, it may be ellip- 105 tal or of other shape, and therefore I do not wish to be understood as limiting myself to the precise details as set forth, as changes in the form, proportion, size and minor details may be made, within the scope of the claims, 110 without departing from the spirit or sacrificing any of the advantages of the invention.

Having thus described the invention, what is claimed and desired to be secured by Letters Patent, is:

A wholly flexible blackboard eraser, comprising a spirally wound flexible strip constituting a body having a flat top and bottom, the extreme outer end of the strip being secured to the outer edge of the body, and the coils of the spiral being otherwise disconnect-
ed, a back formed of freely flexible material covering the entire top of the body and closing the joints between the turns of the spiral to prevent dust working through the eraser, said back being secured to the individual

coils, and said coils being freely separable 15 from one another and capable of spreading to collect chalk dust, the back having spaced incisions, and a flexible strap handle passing through the incisions and secured between the body and the back.

In testimony whereof I have signed my name to this specification in presence of two witnesses.

MARTIN W. PERKINS.
